To all whom it may concern:

Be it known that I, WARREN B. FERRIS, a citizen
of the United States, residing at Columbus, in
the county of Franklin and State of Ohio, have
invented a new, original, and ornamental Design
for Rocket Ship Model, of which the following is
a specification, reference being had to the ac-
companying drawing, forming a part thereof.

Fig. 1 is a side elevation of the rocket ship
model showing my new design.

Fig. 2 is a rear elevation thereof.

Fig. 3 is a front elevation thereof.

Fig. 4 is a top plan view thereof.

I claim:

The ornamental design for a rocket ship model,
as shown.

WARREN B. FERRIS.
